NOISE SUPPRESSION CIRCUIT

George M. Brown, Scotia, N. Y., assignor to General Electric Company, a corporation of New York

Application December 4, 1935, Serial No. 52,859

17 Claims. (Cl. 250—20)

My invention relates to means for suppressing noise in the audio circuit of a high frequency receiver, and more particularly to means for rendering the audio channel of a receiver inoperative in the absence of a received signal carrier. My invention is particularly applicable for use in receivers which operate from an anode voltage source which may vary over rather wide limits, as is the case in police signal communication wherein dynamotors or vibrators operated from an automobile storage battery are employed to supply energy to the plate circuits of the receiver system.

It is an object of my invention to provide an improved noise suppression circuit for a high frequency receiving system which utilizes the change in current produced in the anode circuit of one of the tubes in the system in response to a received signal carrier to control the bias on the control electrode of one of the audio frequency amplifier tubes in such a manner that when a carrier is being received the controlled amplifier is biased to its normal operating point, and when no carrier is being received the controlled amplifier is biased to an anode current cut-off value or beyond.

It is an additional object of my invention to provide a circuit of the above character having means connected therein to prevent the grid of the controlled amplifier from being biased further positive than its normal operating point when carrier waves of high intensity are being received, thereby to prevent undesired distortion in the audio output of the controlled amplifier.

It is a still further object of my invention to provide a circuit having the above characteristics which operates satisfactorily to perform its noise suppressor function irrespective of voltage variations of the energy supply source for the plate circuits of the system.

The novel features which I believe to be characteristic of my invention are set forth with particularity in the appended claims. My invention itself, however, both as to its organization and the method of operation, together with further objects and advantages thereof, will best be understood by reference to the following specification taken in connection with the accompanying drawings in which Fig. 1 illustrates a high frequency receiving system having my invention embodied therein; Fig. 2 illustrates the characteristics of the second detector included in the circuit of Fig. 1, Fig. 3 illustrates a modification of my invention; Fig. 4 illustrates my invention as applied to a receiver having a biased detector therein, and Fig. 5 illustrates certain characteristics of the detector included in the circuit of Fig. 4.

Referring to Fig. 1 of the drawings, I have illustrated my invention embodied in a radio re-

ceiving system having the novel features described in a copending application, Serial No. 27,896, Stewart Becker, filed June 22, 1935, which application is assigned to the same assignee as the present application. This receiver comprises an antenna 1 from which received oscillations are supplied to the input of a radio frequency amplifier 2 in which they are amplified and supplied to a converter stage 3. The converter stage 3 includes a first detector and local oscillator, which may, if desired, be combined in the same envelope. In order to simplify the drawings, the details of the circuit of the amplifier 2 and converter stage 3 have been omitted since they are of conventional form and are well known in the art. Briefly, the amplified signals from the amplifier 2 are detected and heterodyned with locally generated oscillations in the converter stage 3. The modulated intermediate frequency output from the converter stage is supplied to an intermediate frequency amplifier 4 through a coupling transformer 5 having its secondary tuned to the operating intermediate frequency by a condenser 6. The input circuit of the amplifier 4 includes the secondary of the transformer 5 connected between the control grid 7 and a cathode 8 of the amplifier tube through a by-pass condenser 9. Amplified output currents from the tube 4 are supplied through a coupling transformer 10 to the input circuit of a second intermediate frequency amplifier enclosed within the envelope of a multi-electrode electron discharge device 11. A tuning condenser 12 is provided for tuning the input circuit of the second intermediate frequency amplifier to the operating intermediate frequency.

The output circuit of the second intermediate frequency amplifier includes a tuned circuit 13 consisting of an inductance 14 and a condenser 15 connected in parallel between the anode 16 and the cathode 17 of the amplifier. A suppressor grid 18 operating at cathode potential is also included in the amplifier circuit. The inductance 14 is coupled to an inductance 19 connected between the control grid 20 and cathode 17 of a second detector having its electrodes enclosed within the envelope of the multi-electrode tube 11.

The output circuit of the second detector includes the primary 21 of a transformer 22 having its secondary 23 connected between the control grid 24 and cathode 25 of an audio amplifier enclosed within the envelope of a multi-electrode tube 26. A power amplifier 27 is resistance coupled to the preceding audio amplifier 24, 25 by means of a blocking condenser 28 and a potentiometer resistance 29 connected in series between the cathode 25 and an anode 30 of the tube 26. Amplified audio output currents from

the power amplifier 21 are supplied to a loud speaker 31 through a coupling transformer 32.

A high voltage source is provided for supplying the necessary energy to the anode circuits of the tubes included in the system. This source is shown as a battery 33 connected across a bleeder resistor 34 having a ground connection 35 at a point intermediate its terminals. The portion of the resistance 34 which is positive with respect to the point 35 is provided with a number of taps 36 and 37 connected to those electrodes of the different tubes requiring less than the maximum positive potential available from the source 33 such, for example, as the screen grids of the two intermediate frequency amplifiers, the screen grid of the radio frequency amplifier and the anode of the local oscillator included in the converter stage 3.

In accordance with the invention disclosed in the application referred to above, the advantages of a novel super-regenerative action are attained in the circuit thus far described by regeneratively coupling the output and input circuits of the second detector, supplying a quenching voltage having a low radio frequency value to the input circuit of the second detector, operating the system at a particular intermediate frequency and carefully adjusting the regenerative coupling to obtain optimum performance.

Regenerative feed-back between the circuits of the second detector is obtained by providing an inductance 38 tuned to the operating intermediate frequency by a condenser 39 and coupled to the inductances 14 and 19. For the purpose of obtaining a maximum selectivity of the receiver, the inductances 19 and 38 are loosely coupled to the inductance 14 and the inductances 19 and 38 are tightly coupled with respect to each other.

In order to provide the quenching voltage necessary to produce super-regenerative action, an oscillation generator is provided which includes the electrodes 39', 40 and 41 enclosed within the envelope of the tube 26. This oscillation generator comprises the tuned circuit 42 connected between the anode 39' and control grid 40 in the conventional manner, the intermediate point of the tuned circuit 42 being connected through a resistance 43 to the positive side of the source of potential 33. Audio frequency currents are by-passed around the source 33 by means of condensers 44 and 45. Oscillations from the anode of the oscillator 39', 40, 41 are supplied to the control grid 20 of the second detector through a coupling condenser 46.

Although the operating characteristics of the above-described system are such that the signal intensity level is maintained relatively constant in the audio circuit irrespective of the intensity of the incoming carrier, it has been found to be desirable to provide an automatic volume control circuit for maintaining the signal intensity level applied to the second detector below a predetermined value. In the circuit illustrated, the automatic volume control circuit for this purpose includes an anode 47 in the envelope of the tube 4, which anode is connected through an intermediate frequency coupling condenser 48 to the anode of the amplifier in the tube 4 and which cooperates with the cathode 8 of this amplifier to form a diode rectifier operating into a load resistance 48' connected between the anode 47 and the negative terminal of the supply source 33.

With the above-described circuit arrangement,

the potential between the point 35 and the negative side of the source 33 is connected across the cathode and anode of the automatic volume control diode thereby to bias the anode 47 sufficiently negative to prevent current from flowing in the resistance 48' when the received signal has an intensity less than a predetermined value. When current flows in the resistance 48' the potential thereacross is supplied through resistance 49 and conductors 50, 51 and 52 to the control grids of amplifier 2, converter stage 3, and amplifier 4 respectively, thereby to reduce the amplification of these tubes upon reception of signals having an intensity greater than the predetermined value.

The primary function of the conventional automatic volume control circuit described above is to maintain the received signal intensities supplied to the second detector below a value at which overloading of the second detector occurs. Thus, while this conventional automatic volume control circuit may, if desired, be adjusted in the same manner in which it is adjusted for conventional automatic volume control i. e. for minimum practical variation of signal intensity supplied to the second detector, when employed in connection with the super-regenerative detector described it is only essential that it reduce the strong signals sufficiently to avoid overloading of the second detector since the principal automatic volume control action is obtained through the inherent operation of the second detector.

In accordance with my invention a network is provided for suppressing noise in the audio channel of the receiver during those periods when no carrier is impressed on the control electrode of the second detector. The noise suppressor network illustrated is particularly applicable to the receiving circuit described above, since it utilizes the characteristics of the super-regenerative second detector in performing its noise suppressor function. This network comprises a resistance 53 connected in the anode circuit of the second detector 17, 20 and is arranged to transfer through a resistance 55 the potential of its terminal 54, 45 furthest removed from the bleeder resistor 34, to the control electrode 24 of the audio amplifier 25, 24, 30. Preferably, a voltage dropping device 56 is inserted between the potential point 54 and the terminal 58 of a resistance 55 for bringing the potential applied to the control grid 24 through the resistance 55 and winding 23 closer to ground potential.

The device 56 may comprise a gaseous discharge device, such, for example, as a neon bulb, having the well-known operating characteristic of a substantially constant voltage drop between its terminals irrespective of small variations in the current flowing through the tube. If a neon tube be employed as the voltage dropping device, it is desirable to connect a resistor 57 between the junction point 58 and the negative terminal of the source 33 thereby to maintain the neon tube 56 in a conducting state at all times. In order to raise the potential of the cathode 25 to a value 65 such that the potential difference between the cathode 25 and the control grid 24 will be within the normal operating range of the amplifier, a pair of resistors 59 and 60 are provided, which are connected in series between the cathode 25 70 and ground. As thus connected the current flowing in the anode circuit of the amplifier 30, 29, 25 plus the current flowing in the anode circuit of the oscillator 39', 40, 25 produces a drop across the resistors 59 and 60 which raises the potential 75

of the cathode to a positive value, above ground potential, determined by the resistance values of the two elements 59 and 60.

The operation of the noise suppressor network described in the preceding paragraphs will best be understood by considering the characteristics of the super-regenerative second detector illustrated in Fig. 2 of the drawings. In this figure the curve A indicates the magnitude of current flowing in the anode circuit of the detector as a function of the intensity of the carrier impressed on the control electrode of the detector. It will be seen that when a carrier is impressed on the control electrode 20 of the second detector, the current in the anode circuit thereof decreases. This produces an increase in the potential at the point 54 because of the reduced voltage drop across the resistor 53 connected in the detector output circuit. It has been found that this potential swing is sufficient to swing the potential of the grid 24 from beyond cut off bias to normal operating bias when a carrier wave is received or is tuned in, even though the carrier may be very weak. Stated in another manner, the positive potential of the point 54 increases when a signal is received and decreases a corresponding amount when the signal is tuned out or completed. This change in positive potential of the point 54 is transferred directly to the junction point 58 by the constant voltage dropping device 56 and is applied directly to the grid 24 of the audio amplifiers 30, 24 and 25 through the resistance 55 and winding 23.

If the potential at point 54 be properly adjusted with respect to the potential of the cathode 25, the audio amplifier 30, 24, 25 may be biased to cut-off, or beyond by the potential difference therebetween when no signal carrier is being received. With the circuit in this condition, if a carrier be received the positive potential of the point 54 is increased in the manner described above. Since this increase is impressed on the grid 24, the negative bias of the grid 24 with respect to the cathode 25 is decreased by a similar amount which is sufficient, with a usable signal strength, to bring the bias of the grid 24 to a value such that the amplifier is biased to a normal operating condition. The degree of bias of the grid 24 with respect to the cathode 25 is determined by the voltage drop across the respective resistance 53, 59 and 60 and when proper resistance values are selected for these resistors, the voltage swing produced at the terminal 54 of the resistance 53 in response to variations of the current in the anode circuit of the detector renders the audio channel operative when a carrier is being received and renders the audio channel inoperative when no carrier is being received. In this manner noise in the output circuit of the receiver is eliminated during those periods when no signal is being received.

It has been found that with the above circuit arrangement when an incoming carrier of high intensity is being received the grid 24 may be biased less negative with respect to the cathode 25 than its normal operating bias due to the low value of current in the anode circuit of the detector, and the correspondingly small voltage drop across the resistance 53 which results in a relatively high positive potential at the point 54. 65 This action is not desirable since distortion of the audio output of the amplifier 30, 24, 25 occurs when the grid 24 attains a less negative bias with respect to the cathode 25 than its normal operating bias. 70

75 In order to obviate the above difficulty a rec-

ifier 61 of any suitable type is provided which is connected between the junction point 58 and a junction point 62 between the resistances 59 and 60. This rectifier is poled in such a direction that when the point 58 tends to become more positive than the point 62, current flows through the rectifier and when the point 58 is negative with respect to the point 62 current flow is prevented. Thus, the rectifier 61 functions to prevent the point 58 and the grid 24 from attaining a positive potential greater than the point 62 irrespective of the intensity of the incoming carrier and, since the cathode 25 is at all times more positive than the point 62 because of the voltage drop across resistor 59, a negative bias on the grid 24 with respect to the cathode 25 is insured.

It will be observed that in the above described circuit the positive potential of the cathode 25 is dependent upon the magnitude of current flowing through the resistors 59 and 60. This current is comprised of two components, namely; the anode current of the amplifier 30, 24, 25 and the anode current of the oscillator 39', 40, 41. Obviously, as the bias of the amplifier 30, 24, 25 is increased to approach a cut-off value the anode current of the amplifier approaches zero and the potential of the cathode 25 is decreased. However, the amplifier anode current is small as compared to the oscillator current and consequently the change in current produced by the change in bias of the amplifier causes a relatively small change in the potential of the cathode 25. Thus, the oscillator 39, 40, 41 tends to stabilize the potential of cathode 25 and maintain the value thereof within desired limits.

From the foregoing description it will be apparent that I have devised a simple noise suppressor circuit which is positive and reliable in its operation to change the audio channel of a receiver from an inoperative to an operative condition in response to a received signal. Although the circuit arrangement described operates in a highly satisfactory manner when the source of anode potential 33 remains constant, it has been found that if the voltage of the source 33 varies, the noise suppressor circuit is affected in an undesired manner. Thus, if the voltage of the source 33 increases above its normal value, the potential at the point 58 corresponding to the potential of the grid 24 is increased in a positive direction and the positive potential of the cathode 25 is increased. Due to the presence of the device 56 in the circuit, the increase in the positive potential of the grid 24 is greater than the increase in the positive potential of the cathode 25. This produces a decrease in the biasing potential difference between the control electrode 24 and the cathode 25, which decrease may be sufficient to render the amplifier operative to amplify noise when no signal is being received. If, on the other hand, the voltage of the source 33 decreases below normal the negative bias of the grid 24 with respect to the cathode 25 may be increased to such an extent that the decrease in bias produced in response to a received signal may be insufficient to render the amplifier 30, 24, 65 25 operative.

Referring to Fig. 3 of the drawings I have shown a modification of my improved noise suppressor circuit which includes means whereby the noise suppressor function is rendered unaffected by variations in the voltage of the anode supply source. 70

This circuit is shown as including a portion of the circuit of Fig. 1 and similar circuit elements included therein are identified by the same 75

reference characters. In the circuit of Fig. 3 the resistance between the junction point 54 and the anode current supply potentiometer 34 is divided into two sections 63, 64 having a junction point 65 therebetween. In order to prevent variations in the voltage impressed on the potentiometer resistance 34 from affecting the action of the noise suppressor circuit an additional circuit is provided, which circuit includes a resistor 66 and a pair of gaseous discharge tubes 67 and 68.

The stabilizer circuit described above functions in the following manner:—If the voltage of the source increases, the positive potential of the point 54 tends to increase thereby to increase the positive potential of the point 58 and of the control grid 24. Simultaneously with this action the voltage drop across the resistors 59 and 60 tends to increase thereby to increase the positive potential on the cathode 25. In the absence of the connection 66, 67, 68 the increase in the positive potential of the grid 24 would be greater than that of the cathode 25, and accordingly, the negative bias of the grid 24 with respect to the cathode 25 would be decreased in the manner previously described. However, by providing the series circuit 66, 67 and 68 the circulating current flowing through the resistor 64, resistance 66, and the discharge tubes 67 and 68 and the resistor 60 is increased in response to the increased source voltage and the voltage drop across the resistance 64 is increased, thereby to lower the positive potential at the point 54 and increase the positive potential at the point 62. Due to the constant voltage drop characteristic of the gaseous discharge tubes 67 and 68, the current flowing through the resistance 60 increases in greater proportion than the increase in voltage across potentiometer 34 and, consequently, the increase in the drop across resistance 60 is disproportionately larger than the increase in voltage of the supply source. As a result the increase in positive potential of the point 62 is greater in proportion than the increase in potential of the voltage source. This amplified increase of potential at point 62 produces a correspondingly amplified increase in the positive potential of the cathode 25 at the same time that the amplified increase in the positive potential of the control grid 24 occurs.

If the voltage of the supply source decreases below its normal value, the circuit including elements 66, 67, 68 functions to produce a disproportionately greater decrease in the positive potential of the cathode 25 which accompanies and compensates for the disproportionately greater decrease in the positive potential of the grid 24. Thus, the function of the circuit 66, 67, 68 with a decrease in the voltage of the supply source is the converse of that attending an increase in the voltage of the supply source, i. e. the decrease in positive potential at point 58 is partially compensated for by the decrease in voltage drop across resistor 64, and the decrease in positive potential of point 62 is amplified by the action of the gaseous discharge tubes 67 and 68 to cause a relatively greater decrease in current flowing through the resistance 60.

In the above-described manner the potentials of the grid 24 and cathode 25 are made to vary together in the same direction and by a greater amount than the amount of variation of the voltage of the supply source irrespective of whether the supply source voltage increases or decreases from its normal value. By providing resistances 64 and 66 and gaseous discharge tubes 67 and 68

having proper resistance values the positive potentials existing respectively on the grid 24 and the cathode 25 may be made to vary together in such a way that the desired biasing potential exists irrespective of voltage variations of the supply source. Further, by properly adjusting resistors 64 and 66, the potential of the cathode 25 may be made to vary by an amount greater than the potential change of the grid 24, in which case the bias potential between the grid 24 and the cathode 25 will vary with and in the same direction as the supply voltage by an amount sufficient to compensate for variations in the voltage supplied to the anode 30, and for variations in the gain of the receiver produced by voltage supply variations. Hence, it will be seen that the circuit 66, 67, 68 functions to render the operation of the noise suppressor circuit independent of supply source voltage fluctuations and in addition functions to compensate for changes in the gain of the receiver produced by such voltage fluctuations.

Although I have described my invention as being particularly applicable for use in a receiver having a super-regenerative, or grid leak, detector embodied therein, it will readily be understood that my invention may be used with equal success in a receiver including a detector of the biased grid type, with but a slight modification of the circuit arrangement shown. Thus, in Fig. 4 I have illustrated an arrangement having my improved noise suppressor circuit connected therein which includes a biased detector of a type well known in the art. As shown, this circuit comprises a triode detector 69 which may have its input circuit coupled to a source (not shown) of signal modulated carrier current by means of a coupling transformer 70. The output circuit of the detector 69 includes the primary winding 71 of a coupling transformer 72 having its secondary 73 connected between the control electrode 74 and cathode 75 of an audio amplifier 76. The biasing potential for the control electrode of the detector 69 is supplied by a small "C" battery 77 shunted by a by-pass condenser 78. A suitable source of anode potential 79 is provided for supplying energy to the respective anode circuits of the detector 69 and amplifier 76, and is shown as shunting the two resistance potentiometer elements 80 and 81.

In the noise suppressor circuit for the biased detector arrangement of Fig. 4, a resistance 81 is connected in the anode circuit of the detector 69 having its upper terminal 82 connected to supply a control potential to the control grid 83 of a triode 84 through a gaseous discharge tube 85 and a resistance 86. A resistance 87 shunted by a by-pass condenser 88 is provided for biasing the cathode 89 of the triode 84 to a relatively high positive potential slightly greater than the positive potential impressed on the control grid 83 by the resistance 81. The anode circuit of the triode 84 includes a resistance 90 having its upper terminal 91 connected to a second voltage dropping gaseous discharge tube 92. The potential existing at the terminal 93 of the tube 92 is impressed on the control electrode 74 of the amplifier 76 through a resistance 94. A pair of resistances 95 and 96 respectively, are connected in the circuit to maintain the gaseous discharge bulbs 85 and 91 in a conductive condition at all times. A cathode biasing resistor 97 shunted by a by-pass condenser 98 is provided for raising the positive potential of the cathode 75 to a value slightly above that of the grid 74. In order to 75

5 maintain the current flowing through the resistors 87 and 97 substantially constant irrespective of the magnitude of anode current in the output circuits of the tubes 84 and 76, thereby to maintain the potentials of the cathodes 89 and 75 substantially constant, a pair of bleeder resistors 99 and 100 are provided which cooperate with the biasing resistors 87 and 97 respectively to form current circulating paths. By selecting 10 elements 99 and 100 having suitable resistance values, the circulating current may be maintained at such magnitude that changes in current produced by a decrease in anode current of tube 76, as the control bias is varied between cut 15 off and normal values, causes only a slight change in the positive potential of the cathodes. Thus, it will be seen that the bleeder resistors 99 and 100 perform the same function in the circuit of Fig. 4 as the oscillator 39', 40, 41 of Figs. 1 and 3. 20 The operation of the above-described circuit arrangement will best be understood by reference to Fig. 5 wherein there is shown a curve B indicating the relation between anode current and signal intensity for a biased type of detector. It 25 will be seen that when a signal is impressed on the input circuit of the detector 69 the current in the anode circuit thereof is increased. This produces a corresponding decrease in the positive potential existing at the point 82 of the noise suppressor circuit due to the increased drop across 30 the resistance 81. This decrease is impressed by the tube 85 directly on the grid 83 of the triode 84 thereby to increase the bias on the grid 83 and decrease the current flowing in the anode circuit 35 of the tube 84. This decrease in anode current produces a corresponding increase in the positive potential existing at the point 91 of the circuit, which increase is transferred directly to the control grid 74 of the amplifier 76 by the voltage 40 dropping discharge tube 92. It will readily be seen that with the grid 74 of the amplifier 76 biased to cut-off or beyond at the time the signal is received, the increase in positive potential produced by reception of the signal will swing the 45 bias on the grid 74 by an amount such that the amplifier 76 is rendered in a normal operating condition. It will further be seen that if the signal ceases or is tuned out, the current flowing 50 in the anode circuit of the biased detector will decrease to its original value thereby increasing the positive potential at the point 82 and causing the noise suppressor circuit to bias the amplifier 76 to cut-off or beyond.

55 Although I have described my invention as including a voltage dropping device for reducing the positive potential from a relatively high value existing at a point in the anode circuit of the detector to a potential somewhat closer to ground potential, it will readily be understood that if the 60 characteristics of the controlled amplifier permit, the use of such a voltage dropping device may be dispensed with. Thus, considering the arrangement shown in Fig. 1, for example, if the tube 26 possesses a characteristic such that the voltage 65 difference between the cathode 25 and the cathode heater may approximate the voltage difference between the anode of the detector 20, 17 and ground, the gaseous discharge tube 56 may be omitted from the circuit. With this modified arrangement the cathode 25 may be raised to approximately the anode potential of the detector 20, 17 by suitable resistors 59 and 60 and the point 54 connected directly to the point 58. However, it is well known that the ordinary commercial 70 electron discharge tube at present employed in re-

ceiver circuits will not permit such a high voltage difference between the cathode and the cathode heater and, accordingly, it is desirable to employ the voltage dropping device 56 connected in the manner illustrated.

An alternative arrangement which may be employed is that of supplying power to the heater for cathode 25 from a separate source, such as a separate transformer winding or battery, in which case the potential of the heater may be kept approximately the same as that of cathode 25. If this be done the cathode of the controlled amplifier may be operated at a value slightly more positive than the point 54 and the point 58 connected directly to the point 54. Obviously such an arrangement eliminates the necessity for employing the voltage dropping device 56 and the resistance 57.

While I have described what I consider to be preferred embodiments of my invention, it will of course be understood that I do not wish to be limited thereto since many modifications may be made both in the circuit arrangement and in instrumentalities employed, and I contemplate by the appended claims to cover all such modifications as fall within the true spirit and scope of my invention.

What I claim as new and desire to secure by Letters Patent of the United States, is:

1. The combination, in a high frequency receiving system, of an electron discharge device including an anode and a cathode, an anode circuit connected between said anode and cathode and having a source of potential connected therein, a resistance connected in said circuit, an amplifier connected in said system having a control electrode, a circuit for directly impressing the potential of the terminal of said resistance nearest said anode on said amplifier control electrode thereby to control the magnitude of negative bias of said control electrode with respect to said amplifier cathode, said negative bias being sufficient to render said amplifier inoperative in the absence of a received carrier, means responsive to a received carrier for varying said potential thereby to change the negative bias of said control electrode and render said amplifier operative, and means for preventing said negative bias from decreasing below a predetermined minimum value.

2. The combination, in a high frequency receiving system, of an electron discharge device including an anode and a cathode, an anode circuit between said anode and cathode having a source of potential connected therein, an amplifier connected in said system and including a control electrode and a cathode, means for biasing said amplifier cathode to a relatively high positive value, a circuit for deriving from said anode circuit a positive potential slightly below that of said amplifier cathode and for impressing said potential on said control grid thereby to bias said control grid negative with respect to said amplifier cathode, said negative bias being sufficient to render said amplifier inoperative in the absence of a received carrier, means responsive to a received carrier for varying said potential thereby to change the negative bias of said control electrode and render said amplifier operative, and means for preventing said negative bias from decreasing below a predetermined minimum value.

3. The combination, in a high frequency receiving system, of an electron discharge device including an anode and a cathode, an anode circuit connected to said discharge device having a

source of potential connected therein, an amplifier connected in said system and including a control electrode and a cathode, a circuit for biasing said amplifier cathode to a relatively high positive value, a circuit for deriving from said anode circuit a positive potential slightly below that of said amplifier cathode and for impressing said potential on said control grid thereby to bias said control grid negative with respect to said amplifier cathode, said negative bias being sufficient to render said amplifier inoperative in the absence of a received carrier, means responsive to a received carrier for varying said derived positive potential thereby to change the negative bias of said control electrode and render said amplifier operative, and means including a unilateral conducting device connected between a point in said last named circuit and a point in said amplifier cathode biasing circuit for preventing said negative bias from decreasing below a predetermined minimum value.

4. In combination, a high frequency receiving system, including a plurality of amplifiers each having an anode circuit, a current source for supplying energy to said anode circuits, said source having a variable voltage, a noise suppressor circuit for biasing one of said amplifiers to an inoperative condition in the absence of a received carrier and for biasing said controlled amplifier to an operative condition when a carrier is being received, and means connected in said noise suppressor circuit for varying the bias of said controlled amplifier to compensate for changes in the gain of said system produced by variations in the voltage of said supply source.

5. In combination, a high frequency receiving system, including a plurality of amplifiers each having an anode circuit, a current source for supplying energy to said anode circuits, said source having a variable voltage, a noise suppressor circuit for biasing one of said amplifiers to an inoperative condition in the absence of a received carrier and for biasing said controlled amplifier to an operative condition when a carrier is being received, and means connected in said noise suppressor circuit for varying the bias of said controlled amplifier to compensate for changes in the gain of said system produced by variations in the voltage of said supply source and for preventing variation in the voltages of said supply source from affecting the action of said noise suppressor circuit.

6. The combination, in a high frequency receiving system, of an electron discharge device including an anode and a cathode, an anode circuit connected to said discharge device between said anode and cathode, an amplifier connected in said system having a control electrode and an anode, an anode circuit connected to said amplifier, a current source for supplying energy to said anode circuits, a circuit for deriving from said first-named anode circuit a potential which varies in accordance with the intensity of an incoming signal and for impressing said potential on said amplifier control electrode thereby to control the magnitude of said control electrode negative bias with respect to said amplifier cathode, and means responsive to variations in the voltage of said supply source for changing said control grid bias thereby to compensate said system for changes in the gain of said system produced by said voltage variations.

7. The combination, in a high frequency receiving system, of an electron discharge device including an anode and a cathode, an anode cir-

cuit connected to said discharge device between said anode and cathode, an amplifier connected in said system having a control electrode and an anode, an anode circuit connected to said amplifier, a current source for supplying energy to said anode circuits, a circuit for deriving from said first-named anode circuit a potential which varies in accordance with the intensity of an incoming signal and for impressing said potential on said amplifier control electrode thereby to control the magnitude of said control electrode negative bias with respect to said amplifier cathode, means for preventing said negative bias from decreasing below a predetermined value, and means responsive to variations in the voltage of said supply source for changing said control grid bias thereby to compensate said system for changes in the gain of said system produced by said voltage variations.

8. The combination, in a high frequency receiving system, of an electron discharge device including an anode and a cathode, an anode circuit connected to said discharge device between said anode and cathode, an amplifier connected in said system having a control electrode and an anode, an anode circuit connected to said amplifier, a current source for supplying energy to said anode circuits, a noise suppressor circuit for deriving from said first named anode circuit a potential which varies in accordance with the intensity of an incoming signal and for impressing said potential on said amplifier control electrode thereby to control the magnitude of said control grid negative bias with respect to said cathode, means for preventing said negative bias from decreasing below a predetermined value, and means for preventing variations in the voltage of said supply source from affecting the action of said noise suppressor circuit.

9. The combination, in a high frequency receiving circuit, of means to vary the potential at a certain point in said circuit with respect to ground as the intensity of received signal varies, an amplifier for received signals having a control electrode, a cathode, and a circuit therebetween, a first point on said circuit between said control electrode and cathode being maintained at fixed potential with respect to ground, and means to maintain the potential at a second point on said circuit between said control electrode and cathode at substantially fixed potential with respect to said first mentioned certain point for all intensities of received signals and during absence of received signals, the variations in potential between said first and second points with variations in received signal being sufficient to vary the condition of said amplifier from that of substantial inoperativeness to one of normal operativeness.

10. The combination, in a high frequency receiving circuit, of means to vary the potential at a certain point in said circuit with respect to ground as the intensity of received signal varies, an amplifier for received signals having a control electrode, a cathode, and a circuit therebetween, a first point on said circuit between said control electrode and cathode being maintained at fixed potential with respect to ground, and means to maintain the potential at a second point on said circuit between said control electrode and cathode at substantially fixed potential with respect to said certain point for all intensities of received signals and during absence of received signals whereby the potential variations between said certain point and ground appear between

said first and second points, and means utilizing said potential variations to render said amplifier inoperative during reception of signals of less than predetermined amplitude and operative for 5 amplification of said signals when said signals have greater than a predetermined intensity.

11. The combination, in a radio receiver, of a pair of electron discharge devices, one of said discharge devices passing anode current having intensity variable in accordance with the intensity 10 of received signal and the other of said devices having a control electrode, a source of operating voltage, connections for said anode current and said control electrode to said source of operating voltage, a resistance in the connection for said anode current, a resistance in said control electrode connection, and means to maintain a substantially constant potential between the termini 15 of said two resistances remote from said source of operating potential during the variations in intensity of received signal encountered during practice and during absence of received signals, and means including said last means to control 20 said other discharge device in accordance with the intensity of said anode current.

12. The combination, in a radio receiver, of a pair of electron discharge devices, one of said discharge devices passing anode current having intensity variable in accordance with the intensity 25 of the received signal and the other of said devices having a control electrode, a source of operating voltage, connections for said anode current and said control electrode to said source of operating voltage, a resistance in the connection 30 for said anode current, a resistance in said control electrode connection, and means to maintain a substantially constant potential between the termini of said two resistances remote from said source of operating potential during the variations 35 in intensity of received signals encountered during practice and during absence of received signals, and means including said last means to produce a bias on said control electrode satisfactory for operation of said other discharge 40 device when said anode current is of a value corresponding to the intensity of signals to be received and such as to render said discharge device substantially inoperative when said anode current has a value corresponding to less than a 45 predetermined value of received signals.

13. The combination, in a radio receiver, of an amplifier for received signals having a control electrode, a circuit having a point thereon at which the potential with respect to ground varies 50 during variation in intensity of received signals over a range sufficient in width for control of said amplifier if applied to said control electrode but at potentials with respect to ground different from desired potentials of said control electrode, 55 a constant voltage gaseous discharge device having one electrode connected to said point and another electrode connected to said control electrode, means to maintain conduction between said electrodes both during absence and presence of 60 received signals, said gaseous discharge device being adapted to maintain substantially constant the voltage between said electrodes during all values of potential on said point with respect to ground, whereby substantially the entire range of 65 variation in voltage of said point is supplied to said one control electrode, the constant voltage between said electrodes being of such value that the variation of said control electrode is in a desired range with respect to ground, and means 70 whereby the said amplifier is operative when the 75

potential of said control electrode has a value at one end of said range and inoperative when said potential has a value at the other end of said range.

14. In combination, an amplifier having a pair of input electrodes connected through respective resistances to ground, means to maintain said electrodes at certain low potentials with respect to ground, a discharge device having an output circuit having a point thereon at which the potential varies through a range relatively high with respect to ground and of sufficient width for control of said amplifier if applied to one of said control electrodes, means connected between said point and said one input electrode to maintain a constant potential therebetween during said variations in potential, and means connected between said input electrodes operative when said range is exceeded to produce a voltage on the other input electrode to oppose the voltage on said one input electrode.

15. The combination, in a signal receiver, of a circuit having a point thereon at which the potential with respect to ground varies with variations in received signal intensity, an amplifier 25 having a cathode and a control electrode, a circuit between said control electrode and cathode including a connection between said control electrode and said point, means to vary the voltage between said cathode and said control electrode 30 over such a range that said amplifier is inoperative in the absence of received signals and operative during received signals, and means responsive to change in polarity of electromotive force between said point and a second point having 35 potential not to be exceeded by the potential at said first point to limit the variation in voltage between said grid and cathode upon reception of strong signals.

16. In combination, an amplifier having an 40 anode circuit including a resistance and a control electrode circuit including said resistance, both of said circuits including a cathode of said amplifier, means to supply to the control electrode of said amplifier electromotive forces to be 45 amplified thereby and a bias potential, said bias potential varying through a range of values extending in the direction of the potential of said cathode from a value so negative relative to the potential of said cathode that the amplification 50 of said amplifier is substantially reduced thereby, and means responsive to changes in the difference of potential between said control electrode and a point on said resistance to limit the bias voltage applied to said control electrode.

17. In combination, an amplifier having an anode circuit including a resistance and a control electrode circuit including said resistance, both of said circuits including a cathode of said amplifier, means to supply to the control electrode of said amplifier electromotive forces to be 60 amplified thereby and a bias potential, said bias potential varying through a range of values extending in the direction of the potential of said cathode from a value so negative relative to the potential of said cathode that the amplification of 65 said amplifier is substantially reduced thereby, and a unilateral conducting device connected between said control electrode and a point on said resistance, said device being so poled and said point being so selected that said device passes current only when the potential of said control electrode differs from said value by more than a predetermined amount.
